UNITED STATES PATENT OFFICE.

HENDRICK W. LUNDQUIST, OF SAN DIEGO, CALIFORNIA.

VENDING-MACHINE.

964,988.

Specification of Letters Patent.

Patented July 19, 1910.

Application filed November 22, 1909. Serial No. 529,350.

To all whom it may concern:

Be it known that I, HENDRICK W. LUNDQUIST, residing at San Diego, in the county of San Diego and State of California, have 5 invented a new and Improved Vending-Machine, of which the following is a specification.

My invention relates to coin controlled machines for vending articles of merchandise, and more particularly to that class of machines especially adapted for selling postage stamps, postal cards, stamp books, soda water and insurance checks or other commodities, capable of being delivered from a 15 continuous strip or superimposed layers, and my said invention has for its object to provide a machine of this class in which the delivery mechanism is especially designed and arranged that it can be economically 20 made up and assembled, and the parts so combined that they will positively operate to deliver the article sold and in which the goods to be sold can be readily and quickly placed within the machine.

Another object of my invention is to provide a motor operated mechanism that is set in operation in the dropping of the required coin and which, when the machine is arranged to sell a plurality of articles 30 such as stamps of different denominations, or single stamps, stamp books, postal cards, comprises simple and improved selective motor driven shafts mechanism all actuated from a single motor for putting into action 35 that delivery mechanism selected by the purchaser in dropping the required coin.

With other objects in view which will be hereinafter referred to, my invention in its generic nature, comprehends an improved 40 arrangement of delivery mechanism including a motor, coin controlled means for setting it into action, and step by step devices that feed the article from the main supply and discharge it within reach of the buyer.

In its more complete nature, this invention comprehends an improved construction and arrangement of a stamp ribbon holding reel, frictionally engaging rolls between which the ribbon of stamps pass and by which the 50 said ribbon is moved forward, step by step operating gear mechanism that actuated the rolls, an electric motor, and circuit controller for the motor normally actuated by the slot inserted coin.

In its still more subordinate features, my 55 invention consists in certain details of construction and peculiar combination of parts, all of which will be hereinafter fully described, specifically pointed out in the claims and illustrated in the accompanying drawings, in which:—

Figure 1, is a perspective view of a mail receptacle embodying my invention. Fig. 2, is a side elevation, parts in section, of a stamp selling unit constructed on my improved lines. Fig. 3, is a front elevation, parts in section, of a stamp and postal card selling unit in a case. Fig. 4, is a side elevation of the postal card selling device alone. Fig. 5, is a diagrammatic view illustrating 70 the manner of gearing a multiple of units. Fig. 6, is a detail section of the clutch mechanism. Fig. 7, is a diagrammatic view hereinafter referred to. Fig. 8, is a detail section hereinafter referred to.

75

In the practical application of my invention, the machine is more especially adapted for postal service uses, its working mechanism consisting of a number of units, the principal one of such mechanisms being arranged for selling postage stamps singly from a continuous ribbon of stamps, the preferred arrangement of my machine including a number of mechanisms all actuated from the same motor devices, the several mechanisms being arranged in the upper end of a casing, the lower or body portion of which is utilized as a letter and package box, the several different delivery mechanisms having their outlet slots arranged in 90 the manner clearly shown in Fig. 1.

Referring now more particularly to Figs. 2 and 3 of the drawings which show the actuating mechanism for the single stamp delivery 1 designates the sheet metal box or 95 casing, the upper end of which is a hinged hood 10 that swings back when unlocked, so that a new supply or reel of stamps can be readily inserted when necessary. At the front wall of the casing is a supplemental 100 wall 2 which has an outwardly curved foot portion 20 that receives the severed or sold stamps and brings them into position to be readily grasped by the buyer. 3 designates the coin slot that opens into a coin chute 30 that extends down through a base 40 of a supporting frame 4, presently again referred to and which discharges into a coin receiver

80

85

95

100

105

5 which may and preferably is slidable through the front of the casing, as shown in Figs. 1 and 2. 6 designates a weighted lever fulcrumed at 60 on the frame 4, its 5 front end being bent downwardly and terminating in a finger 61 that projects through a slot 31 in the chute 30 and in the path of the coin, which, in its passage, swings the finger end of the lever down and 10 raises the upper or weighted end 62, which, in my construction, supports a pendent member 63 that normally rests upon a delicately flexed terminal 7, of a circuit closer, the other and adjustable terminal 70 being 15 fixedly held on frame 4, the several parts just explained being relatively so arranged that as lever 6 is tripped by the coin, the circuit through the battery 8 and motor 80 is closed, which starts the said motor and 20 drives the shaft 10^a suitably journaled in framing 4 and on which is loosely mounted a driver gear 11 provided with a clutch hub 12 for coacting with the clutch hub 13 keyed on shaft 10^a but slidably thereon, said hub 25 13 being grooved to receive the forked end 14^a of a bell crank lever 14 that is joined to the end 62 of the coin tripped lever 6, as best shown in Fig. 6.

So far as described, it will be seen that 30 lever 6 when tripped by the coin as it passes down the chute, instantly and simultaneously clutches the driver gear 11 with the shaft 10^a as the motor is started by the closing of the battery circuit.

35 The frame 4 at the inner end has a pair of vertical standards 42—42, the upper ends of which have socket bearings 43—43 to receive the ends 15^a of the journal or shaft 15 on which is fixedly held the reel sides 40 or disks 16—16 between which is rolled the reel of stamps in ribbon form, said ribbon, designated *x*, being wound on a block *y* loosely mounted on the shaft or journal 15 that carries a drive gear 17 on one end and 45 a set screw 18 on the other end, the latter being utilized to clamp the several reel members to the operative condition, it being clear from Fig. 3 that when the reel is empty all that is necessary to refill is to lift the reel 50 out of its bearings, remove the set screw 18 from the journal 15 and pull it with the gear thereon from the reel block so the latter can be stamp rewound, and when filled, set back between the reel sides on the journal 15 55 which is again secured by the screw 18.

The driven gear 11 meshes with a gear 19 which in turn meshes with a gear 20^a of like diameter, on the journal or shaft 21^a on which is a pulley 22^a over which takes a belt 60 23 that imparts motion to the belt pulley 24 on a short shaft 25, suitably journaled on the standards of frame 4 and on which is a gear 26 that imparts motion to the gear 17 on the reel journal.

65 Gear wheel 20^a meshes with another one

27 of the train of gears, the latter acting as a tappet or spacer device since it controls the space through which the stamp ribbon *x* is fed, the feed in the construction shown being the length of the postage stamp and for such purpose wheel 27 carries a notched disk 27^a having cam surfaces 27^b that merge with the radial stop shoulders 27^c. A detent or locking arm 28 coacts with the disk 27^a, the said arm being pivotally mounted 75 on a pendent portion of frame 4.

By reference to Fig. 2 it will be seen the front end of the arm 28 rides on the notched periphery of the disk 27^a, and is yieldingly held in contact therewith by the coiled spring 80 29 that joins with the rear or inner end of the said arm 28. Gear 27 meshes with a gear 30^a on the lower one of a pair of feed rollers 32—33 disposed in the vertical plane and in superimposed relation, so as to frictionally engage the contacting faces being preferably rubber so as to firmly grip the stamp ribbon that is fed between them and to provide for a positive contact of the upper roller 32 with its mate 33, the said upper roller is journaled in arms 45 of the frame, that are pivotally connected to the frame 4 and are pulled downwardly by the springs 47, as shown. Another object in movably mounting the roller 32 is that the 95 same can be readily lifted from the other roll 33 when putting in a new charge of stamps, it being understood that the front end of the new ribbon must be passed between the rolls 32 and 33 and properly adjusted with respect to said rolls and the cutting device presently described when "reloading."

Just in advance of the delivery or contacting point of the rollers 32—33 the frame 4 has an anvil or bed portion *Z* over which the stamp ribbon passes and whose front face form a cutting edge *a* for co-operating with the knife blade 50, the construction and the manner of its operation of which is best 105 understood by referring to Figs. 3 and 7, by reference to which it will be seen the knife blade is transversely disposed with reference to the line of delivery of the stamp ribbon and it is hinged at one end as at 51 110 so that when it is swung down, its cutting edge closes over the anvil edge *a* and severs the stamp ribbon by a shearing operation, and as the said blade 50 is normally down, closes the passage from the rollers 32 and 33 115 and prevents the stamp ribbon going too far, it acting as a gage for holding the next stamp on the ribbon in a true position with respect to the feed rollers 32 and 33.

By referring again to Fig. 2, it will be 125 noticed since the wheel 27, when in motion, turns in the direction of the arrow *s*, just so soon as it begins its motion the cam surface engaging arm 28 swings the said arm down and it is the movements of the said arm that 130

controls the knife 50, since the free end of the knife has a stud 51^a that extends into the elongated slot 52 on an arm 53 fulcrumed on the frame 4 and formed with a short extension or crank 53^a to which pivotally joins one end of a link rod 54, the other end pivotally connects with the arm 28 at a point in advance of its fulcrum so when the arm 28 is depressed by the disk 27^a, 10 the arm 53 will swing up and raise the knife 50 out of the path of the now forwardly impelled stamp ribbon, it being obvious that when the stamp ribbon is fed forward the length of one stamp, the next notch 15 in disk 27^a will come into line and the arm 28 will be quickly snapped back in the said next notch by the spring 29 and in so moving the arm 53 is quickly swung to bring the cutter down to sever the stamp from the ribbon, the stamp dropping into the receiver 20 that opens through the front of the casting, as shown.

For positively holding the coin tripped lever to its normal position at all times, except when tripped by the coin engaging it, and also for making a positive stop of the gearing at each completed intermittent or stepped movement, the gear 12 is also provided with a disk 12^a that is also provided 25 with a series of radial notches 12^b equal in number to and spaced relatively to the notches in the spacer disk 27^a, with which engages a lug 58 on the coin lever.

Just above the coin slots in the casing 30 front are openings 65 for the "empty" indicator or blades 66 that notify the buyer, the machine is not loaded. The blade 66, shown in Fig. 2 rides in a guide 67 and is pushed up by an arm 68 fulcrumed at 69 and having its crank or short end 69^a connected to a hanger rod 69^b that normally rides on stamp ribbon and which is held up by the ribbon until the last stamp of the ribbon enters the rollers 32-33 when by reason 45 of the support, (the ribbon) being exhausted, the arm 69^b which is of sufficient weight to overbalance the long end of the member 69 and the plate 69^b, drops down into a socket α^5 in the anvil 2 and thus shows the 50 empty sign.

Arm 69^b has a short stud 68^a that projects out over the arm that carries the upper roller 32 and the said roller carrying arm has an extension 68^b adapted when the said 55 roller carrying arm is raised to engage the lug 68^a in rod 69^b, such arrangement of parts being provided so that when the attendant wants to fill up or reload the machine by pulling upwardly the finger engaging portion 53^a, Fig. 7, the knife blade 50, the rod 69^b and the arm with roller 32 will be swung up to permit shoving the end of the new ribbon between the rollers 32 and 33 and in 60 position for being fed forwardly as soon as 65 the machine is again "coin started."

Should it be desired to place a number of postage stamp reels, postal card selling units and stamp book selling units under one cover, as in Fig. 1, the various units may receive motion from one main motor shaft, 70 as shown in Fig. 5, it being understood that in such instance the shaft 12^r will extend the entire length of the several units so that motion may be imparted thereto.

Fig. 4 shows a postal card selling unit which 75 comprises a card receptacle 70^a having a follower weight 60^r adapted to keep the cards together so that not less than a certain number may be delivered. Mounted on the weight 60^r is a striking hammer 60^w which 80 will, when all cards are sold, strike the pendant part 69^x and, as already described, raise the "empty" sign 66. The chain 20^r on which are mounted transverse pushers 20^w receives motion from main shaft 12^r through 85 gears 19^x-19^y while a locking disk 12^x having the depression 12^b coats with the coin operated finger 6 hereinbefore described. The cam disk 27^x, which performs a similar function to the disk 27^a, has a depression 27^y 90 wherein an arm 47^w rests, which arm is normally held in contact with the disk 27^x by a spring 47^x. Mounted integrally with the arm 47^w is a transverse closure member 47^y which, when raised by the cam 27^x, allows 95 a predetermined number of postal cards to be delivered into the chute 40^x to the purchaser.

Having thus described my invention, what I claim is:

1. A vending machine, comprising the following elements in combination; an article feeding device, a gear mechanism for actuating the feeding device, a stop preventing movement of said gear mechanism, a motor, 100 and a trip actuated means adapted when shifted to couple the motor with the gear mechanism to actuate it for a predetermined time and to disengage said stop from said gear mechanism to release the same.

2. In a vending machine, the combination with an article feeding device, a gear mechanism for actuating same, means for normally locking the said mechanism from action, an electric motor, a circuit breaker co-operating therewith, and means adapted when shifted to simultaneously unlock the gear mechanism and close the circuit to the motor.

3. In a vending machine, the combination 120 with an article feeding device, a gear mechanism for actuating same, means for normally locking the said mechanism from action, an electric motor, a circuit breaker co-operating therewith, and means adapted 125 when shifted to simultaneously unlock the gear mechanism and close the circuit to the motor, said means consisting of a notched disk coupled with the gear mechanism, a pivoted tripping lever having a stop for co- 130

acting with the notched disk and a member connected with the said lever that normally engages the circuit breaker and adapted, when the lever is tripped, to move away from the circuit breaker.

4. In a vending machine, the combination with a feeding device adapted to operate under a step by step movement, a gearing for effecting such movement, a motor, a driven shaft coupled with the motor carrying clutch, a clutch gear on the shaft that forms a part of the gearing mechanism and a pivoted lever normally in engagement with and adapted to lock the feeding device actuating gearing, the said lever being co-operatively connected with the clutch gear and with the motor and adapted when tipped to release the feeding device actuating gearing to shift the clutch and to set the motor in operation.

5. In a vending machine, the combination with an article feeding device, drive gearing therefor, normally inactive and including a driven shaft, having a clutch and a shiftable clutch gear that co-operates with the shaft clutch, a motor normally inactive and means for simultaneously shifting the clutch gear to lock with the driven shaft and start the motor.

30 6. In a vending machine, the combination with an article feeding device, drive gearing therefor, normally inactive and including a driven shaft, having a clutch and a shiftable clutch gear that co-operates with the shaft clutch, a motor normally inactive and means for simultaneously shifting the clutch gear to lock with the driven shaft and start the motor, an electric motor, a circuit closer therefor, normally inactive, and means for simultaneously shifting the clutch gear to lock with the driven shaft and start the motor, said means including a pivoted lever, connections that join one end with the shifting clutch gear, and a member mounted on the said lever that co-operates with the circuit closer.

7. In a vending machine, a step by step continuous member, a feeding device, a drive gearing for actuating the feeding device, a cutter for severing the continuous member, spring thrust in one direction, devices combined with the drive gearing for moving the cutter at predetermined times in the other direction, a motor including a driven shaft, a clutch gear adapted to be adjusted to interlock with the driven shaft and a means for starting the motor and moving the clutch gear into mesh with the driven shaft.

60 8. In a vending machine a continuous strip, devices for feeding the strip step by step, mechanism for intermittently actuating the feeding devices, said mechanism including a motor and a spacing disk having cam shaped portions, a pivoted lever spring

held to engage the cam shaped disk, and a strip severing means controlled by the movement of the spring actuated lever.

9. In a vending machine, a goods holder, a step by step feeding mechanism that co-operates with the goods holder, motor driven gearing for driving the feeding mechanism, including a peripherally notched disk, a tripping lever for engaging the disk and means for throwing the driving gear into operative connection with the motor.

70 10. In a vending machine for selling postage stamps from a continuous ribbon, a feeding mechanism that consists of a pair of superimposed rolls, one of which is movably mounted with respect to the other, a ribbon severing knife, spring returned in one direction of movement, and normally held over the discharge side of the feed rolls, an anvil over which the ribbon travels, and 80 in advance of the rolls, said anvil co-operating with the knife, lever devices that carry the knife spring held in one position, feed roll drive gearing, means combined therewith for intermittently shifting the lever devices to move the knife to another position and coupling devices for joining the lever devices with the movably mounted roll whereby the said devices will be shifted to 85 lift the knife as the roll is lifted to form a clearance between the rolls.

90 11. In a vending machine for selling postage stamps from a ribbon, the combination with a ribbon reel holder, feed devices comprising a stationarily held roller, a hinged 100 arm, a roller mounted on said arm to frictionally engage the other roller, a casing having an indicator opening, a bed portion in line with the meeting faces of the feeding rolls, a pivoted lever and a severing knife 105 mounted on the outer end thereof that shears over one edge of the anvil, said knife being normally held down over the stamp discharging side of the rolls, another spring held lever connected to the knife carrying 110 lever, a lift connection that joins the upper roll carrying arm and the knife lever, an indicator plate, movable over the indicator opening in the casing normally held in view by the stamp ribbon, and adapted to be 115 moved away from the opening as the upper roll arm and the knife are manually raised, a drive gearing for the feeding devices including a motor, normally held inactive and means for rendering the motor and the gear- 120 ing active.

12. A vending machine of the character described, comprising a number of units, each adapted for delivering its specific article, a single motor for all of the units, selective drive shaft members, clutch devices for interlocking each of said members with the motor driven shaft, and a trip lever for each unit arranged when actuated to shift its respective clutch and start the motor, a feed- 125

ing device for each unit, and drive gearing for imparting a step by step movement to the said feeding devices, actuated by the motor, as set forth.

5 13. In a vending machine, a strip feeding mechanism, said strip feeding mechanism including a fixed roller and a movable roller, means for holding said rollers normally in contact, means in virtue of which said movable roller may be elevated, an indicator, means including a member engaging the

article strip to hold said indicator inoperative and to move said indicator to an operative position when the vendible strip is exhausted, and means carried by said movable roller elevating means for simultaneously elevating the strip engaging part of said indicator when a new strip is to be inserted. 15
